DESIGN.

H. IHLENBURG.

FONT OF COMBINATION TYPE ORNAMENTS.

D No. 18,884.

Patented Jan. 29, 1889.

UNITED STATES PATENT OFFICE.

HERMAN IHLENBURG, OF PHILADELPHIA, PENNSYLVANIA, ASSIGNOR TO
THE MACKELLAR, SMITHS & JORDAN COMPANY, OF SAME PLACE.

DESIGN FOR A FONT OF COMBINATION TYPE ORNAMENTS.

SPECIFICATION forming part of Design No. 18,884, dated January 29, 1889.

Application filed November 30, 1888. Serial No. 292,335. Term of patent 7 years.

To all whom it may concern:

Be it known that I, HERMAN IHLENBURG, a citizen of the United States, and a resident of Philadelphia, Pennsylvania, have invented a new and original Design for Type Ornaments, of which the following is a specification.

My design is clearly shown in the accompanying typographical impression, the different types being numbered, respectively, from 1 to 10 25. I have also shown the types in combination, forming the design in its entirety.

The main feature of each of the types is that it is composed of one or more waved lines, some of which are in the form of scrolls, while others have waved lines radiating from a center, the whole forming a design having the effect of lace-work. The characters numbered 1, 2, and 15 are composed of a series of waved parallel lines. No. 3 is composed of a line in 20 the shape of an **S**, with dots at top and bottom, while No. 4 is a plain scroll with a dot at its lower portion. Nos. 5 and 6 are right and left hand scrolls. No. 7 is a double scroll. Nos. 8 and 9 are left-hand scrolls of a somewhat different shape from Nos. 5 and 6. No. 10 is a circular character having a scalloped outer line with lines radiating from its center, while No. 11 is composed of a diagonal line having a series of lines radiating from its 25 center above and a single dot below. No. 12 is a circular design with lines radiating therefrom. No. 13 is composed of a series of seg-

mental lines of different thickness. No. 14 is a double scroll. Nos. 16 and 17 are right and left hand scrolls with tails. No. 18 is a figure 35 from which radiates a series of light and dark waved lines. No. 19 is a zigzag character ending in a scroll-tail. No. 20 is a character formed of three waved lines ending with a turned-up end and united at the top. Nos. 40 21 and 22 are enlarged scrolls of waved lines ending in tails similar to Nos. 15, 16, and 17. No. 23 is a central scroll of heavy lines, with a series of waved lines radiating therefrom. No. 24 is a double cone of straight lines. No. 25 45 is composed of a series of waved lines ending in small scrolls. The characters numbered 10, 12, 13, 18, and 23 are the center characters proper, while the characters 1 to 7, 11, 14, and 15 are body-characters, while Nos. 8, 9, 50 16, 17, 19 to 22, and 24 and 25 are finishing characters or ornaments.

I claim as my invention—

The design for a font of combination type ornaments, substantially as herein shown and 55 described.

In testimony whereof I have signed my name to this specification in the presence of two subscribing witnesses.

HERMAN IHLENBURG.

Witnesses:

C. F. HUCH,
HERMAN METIUS.
